UNITED STATES PATENT OFFICE.

CHESTER A. PERKINS, OF SOUTH BEND, INDIANA.

COLLAPSIBLE-TUBE HOLDER.

Application filed May 25, 1925. Serial No. 32,866.

The invention relates to collapsible tube holders, particularly adapted for holding and supporting in an inverted position a tooth paste tube, and provided with a vertically guided rotatable member around which the tube is wound for forcing the contents thereof from the discharge spout of the tube. Also to provide means for holding the discharge spout of the tube, which means 5 comprises a horizontally disposed plate having an aperture therein with a restricted side into which the threaded discharge spout is forced by a spring member, and the thread of the spout engaged with the sides 10 of the restricted portion of the aperture for positively holding the tube against upward movement upon rotation of the rotatable member.

A further object is to form the body of the 20 holder from a channeled member in which is slidably mounted a wire guide loop, which guide loop has its ends bent to form outwardly extending arms terminating in oppositely extending arms in a parallel plane to the guide loop, and which last named arms support the rotatable member.

A further object is to provide a hinged closure for the discharge spout of the tube 30 and a leaf spring cooperating with the inner end of the closure adjacent its hinging point for holding the closure in engagement with the discharge end of the spout or in lowered open position.

With the above and other objects in view 35 the invention resides in the combination and arrangement of parts as hereinafter set forth, shown in the drawing, described and claimed, it being understood that changes in the precise embodiment of the invention 40 may be made within the scope of what is claimed without departing from the spirit of the invention.

In the drawing:—

Figure 1 is a front elevation of the holder 45 showing the closure in open position.

Figure 2 is a side elevation of the holder.

Figure 3 is a top plan view of the holder.

Figure 4 is a perspective view of the guide 50 yoke and rotatable member.

Figure 5 is a vertical transverse sectional view through the lower end of the holder.

Referring to the drawing, the numeral 1 55 designates the vertically disposed body of the holder, which body is formed from sheet metal and has inwardly extending flanges 2, the adjacent edges of which are in spaced

relation thereby forming a vertically disposed guide channel 3, in communication with the channel 4 of the body member. Slidably mounted in the channel 4 is an oblong shaped loop 5, formed from a single piece of wire, the ends of which are provided with outwardly extending arms 6, the outer ends of which terminate in oppositely extending arms 7 in substantially a parallel 60 plane to the body 1. Arms 7 at their outer ends are provided with right angularly disposed arms 8, the ends of which terminate in eyes 9, in which is rotatably mounted the tube winding device 10, which comprises 65 spaced bars 11 between which the bottom of the tube 12 is placed and held during the rotation of the member 10. The member 10 has its ends provided with loops 13 adapted 70 to be grasped by the operator for rotating the member 10 during a tube winding operation. As the tube 12 is wound around the member 10, the supporting and guide member is forced downwardly, and is accurately 75 guided in the channel 3 and the channel 4 of 80 the body.

Body 1 adjacent its lower end is provided with a horizontally disposed plate 14, which plate is provided with an aperture 15, the outer side of which has a restricted portion 85 16. When the tube 12 is in inverted position as shown in Figure 2, the discharge spout 17 thereof is disposed in the aperture 15, and it will be seen that when the spout 17 is forced outwardly into the restricted 90 portion 16 of the aperture 15, its thread 18 will interengage with the restricted walls of the restricted portion 16 of the aperture, and the tube will be positively held against 95 upward movement during the rotation of the winding member 10. To hold the tube 12 in outer position as above set forth, the plate 14 is provided with an upwardly extending spring arm 19, which arm at its upper end terminates in a horizontally disposed arm 100 which engages the rear side of the tube 12, and forces the lower end thereof outwardly for positively holding the spout 17 in interengagement with the walls of the restricted portion of the aperture 15. Spring arm 19 105 has sufficient spring action whereby when the arm 20 thereof is forced inwardly, the spout end of the tube may be easily placed in position, and when released will exert sufficient pressure on the rear side of the tube 110 to insure a positive holding thereof.

Disposed beneath the plate 14 are spaced

vertically disposed flanges 21, between which flanges is pivotally mounted the pintles 22 of the tube closure 23, which tube closure, when in horizontal position shown 5 in Figure 2, forms a closure for the discharge spout 17, and when in the lower dotted line position shown in Figure 2, allows the discharge of the contents of the tube 12 onto a brush held below the spout 17. 10 Closure 23 adjacent its pintles is provided with an angularly disposed flange, which engages a leaf spring 25 between the flanges 21, and when the closure is in the closed full line position shown in Figure 2, the leaf 15 spring 25 exerts a pressure on the flange 24 and holds the closure in horizontal position. When it is desired to move the closure to an open position the operator grasps the outer 20 end thereof and forces the closure downwardly to a vertical position, at which time the flange 24 will be disposed above the pintles 22, and the spring will hold the closure in open position.

From the above it will be seen that a collapsible tube holder is provided which is simple in construction, the guide member for the rotatable winding device formed from a single piece of wire and slidably mounted in a channel of a body member. 25 It will also be seen that means is provided cooperating with the thread of the discharge spout of the tube for positively holding the lower end of the tube against upward movement when the winding member is rotated. 30 35 The invention having been set forth what is claimed as new and useful is:—

1. A collapsible tube holder comprising a channeled body member, a guide member slidably mounted in the channeled body

member, said guide member being formed 40 from a single piece of wire and comprising a looped portion vertically disposed and slideable within the guide member, angularly disposed arms carried by the ends of the looped member, said angularly disposed arms terminating in oppositely extending arms, eyes carried by said oppositely extending arms, a rotatable tube collapsing member mounted in said eyes, means for gripping and holding the lower end of a tube when 50 in inverted position, said channeled member having hingedly connected thereto a closure cooperating with the lower end of a tube.

2. A collapsible tube holder comprising a channeled body member, a guide member 55 slidably mounted in the channeled body member, said guide member being formed from a single piece of wire and comprising a looped portion vertically disposed and slideable within the guide member, angularly disposed arms carried by the ends of the loop, said angularly disposed arms terminating in oppositely extending arms, eyes carried by said oppositely extending arms, a rotatable tube collapsing member mounted in said 60 eyes, means for gripping and holding the lower end of a tube when in inverted position with its spout downwardly disposed, a closure for said spout, said closure comprising a plate hingedly connected to the body 65 member adjacent the spout, an angularly disposed flange carried by said plate, a spring cooperating with said flange, said spring forming means whereby said closure may be held in open or closed positions. 70 75

In testimony whereof I affix my signature.

CHESTER A. PERKINS.
